To all whom it may concern:

Be it known that I, Theodore P. Hall, a citizen

have invented a new, original, and ornamental
Design for Airplane, of which the following is a

In the drawings:

Figure 1 is a top perspective view of an air-
plane, showing my new design;

Figure 4 is a side elevational view.

The side of the airplane that is not illustrated
in the drawings substantially corresponds to the
side that is shown in Figures 1 and 4.

I claim:

The ornamental design for an airplane, sub-
stantially as shown and described.
